UNITED STATES PATENT OFFICE.

HALFTEN EUGENE OLSEN, OF CHICAGO, ILLINOIS, ASSIGNOR, BY MESNE ASSIGNMENTS, TO F. C. AUSTIN MACHINERY COMPANY, A CORPORATION OF ILLINOIS.

COMBINED FLUSHING AND SPRINKLING NOZZLE.

Application filed May 18, 1918. Serial No. 234,130.

To all whom it may concern:

Be it known that I, HALFTEN EUGENE OLSEN, a citizen of the United States of America, and resident of Chicago, Illinois, 5 have invented a certain new and useful Improvement in Combined Flushing and Sprinkling Nozzles, of which the following is a specification.

This invention relates to nozzles in general, but more particularly to those for use in flushing and sprinkling streets.

Generally stated, the object of the invention is to provide a novel and desirable form of nozzle of this general character.

15 A special object is to provide an improved construction and arrangement whereby the nozzle can be opened to facilitate the cleaning thereof.

Another object is to provide an improved 20 construction and combination whereby the nozzle can be used for either flushing or sprinkling a street.

It is also an object to provide certain 25 details and features of construction tending to increase the general efficiency and desirability of a combined flushing and sprinkling nozzle of this particular character.

To these and other useful ends the invention 30 consists in matters hereinafter set forth and claimed, and shown in the accompanying drawings, in which—

Fig. 1 is a longitudinal section of a nozzle embodying the principles of the invention.

35 Fig. 2 is a plan of said nozzle, being a partial horizontal section on line 2—2 in Fig. 1.

Fig. 3 is an end elevation of said nozzle.

Fig. 4 is a view similar to Fig. 1, but 40 showing the alternative or substitute form of nozzle.

Fig. 5 is a plan of the construction shown in Fig. 4, showing a portion thereof in horizontal section.

45 As thus illustrated, the invention comprises a hollow body 1 forming a head, having a hexagonal portion 2, which body is adapted to be secured to the supply pipe or coupling connections of a street flushing and sprinkling machine. The formation of 50 the nozzle also involves the upper and lower walls 3 and 4 forming a chamber 5 therein, which terminates in an outlet 6 in the form of a slot. The upper and lower 55 edges 7 and 8 of this slot are curved, it will

be seen, when viewed from above, so that the discharge is fan-shaped. The nozzle is divided horizontally along the line 9, forming a lap joint, and transversely along the lines 10 and 11, so that the entire outlet 60 portion (with the slot 6) and the upper half of the chamber 5 (the wall 3) are removable as a unit. This removable section of the nozzle is held in place on the wall 4 of the head 1 by a vertically disposed or 65 transverse bolt 12 which is fixed at its lower end in the wall 4, and which extends upward through the chamber 5 and has its upper end threaded and provided with a thumb nut 13 to clamp the wall 3 down in 70 place on the lower half of said chamber, so that a tight joint is formed all around.

It will be understood that the nozzle can be used in any desired position. For convenience of illustration, it is shown in horizontal position, so that the chamber 5 tapers away from the slot 6, when viewed from above (Fig. 2), and tapers toward said slot (Fig. 1) when viewed in a direction at right angles to the plane of said 80 slot and the plane of the discharge therefrom.

In Figs. 4 and 5 the removable section is like the one previously shown and described, but in this case a number of small holes 14, 85 in place of the slot 6, are employed, so that the nozzles can be used for flushing or sprinkling. When the vehicle on which the nozzle is mounted is to be used for flushing the streets, the outlet portion having the slot 6 will be used; but when it is desired to sprinkle the streets, then the outlet portion having the holes 14 will be used. In this way the two sections are interchangeable on one and the same nozzle body or 90 head.

Removal of either section, of course, opens the nozzle so that it may be easily cleaned.

What I claim as my invention is:

1. A nozzle having an outlet opening, and a chamber in rear of the outlet opening, said nozzle being divided into sections of different size and form to provide a removable section which contains said entire outlet 100 opening and one wall of said chamber, as well as a part of the opposite wall of said chamber, thereby to afford access to the interior of the nozzle for cleaning purposes, means secured in an opposite section to con- 105 110

nect the nozzle in place, and fastening means to detachably hold said removable section in place.

2. A nozzle having an outlet portion, and a chamber in rear of the outlet, said nozzle being divided to provide a removable section which includes said entire outlet portion and one side of said chamber, thereby to afford access to the interior of the nozzle for cleaning purposes, and means to removably hold said removable section in place, the line of said division extending transversely and half way through the nozzle in rear of said chamber, then longitudinally of said chamber, and finally transversely through the other half of the nozzle.

3. A nozzle structure as specified in claim 1, said holding means comprising a single bolt extending transversely through both sections and through said chamber.

4. A nozzle having an outlet portion, and a chamber in rear of the outlet, said nozzle being divided to provide a removable section which includes said entire outlet portion and one side of said chamber, thereby to afford access to the interior of the nozzle for cleaning purposes, and means to removably hold said removable section in place, said outlet portion being shaped to produce a fan-shaped discharge, with said chamber tapered toward the outlet when viewed in the plane of said discharge, and tapered away from said outlet when viewed in a direction at right angles to said plane, said line of division extending for a distance in said plane, and for distances at right angles thereto.

5. A nozzle having an outlet portion, and a chamber in rear of the outlet, said nozzle being divided to provide a removable section which includes said entire outlet portion, and one side of said chamber, thereby to afford access to the interior of the nozzle for cleaning purposes, and means to removably hold said removable section in place, the line of said division extending transversely and half way through the nozzle in rear of said

chamber, then longitudinally of said chamber, and finally transversely through the other half of the nozzle.

6. A nozzle having an outlet portion, and a chamber in rear of the outlet, said nozzle being divided to provide a removable section which includes said entire outlet portion and one side of said chamber, thereby to afford access to the interior of the nozzle for cleaning purposes, and means to removably hold said removable section in place, said outlet portion being shaped to produce a fan-shaped discharge, with said chamber being tapered toward the outlet when viewed in the plane of said discharge, and tapered away from said outlet when viewed in a direction at right angles to said plane, said line of division extending for a distance in said plane, and for a distance at right angles thereto.

7. The combination of a fluid nozzle comprising two permanently united oppositely disposed walls from between which the fluid is discharged from the end of the nozzle and constituting an outlet member, one of said walls having a rear end extension, a head having a wall forming with said extension a lap joint between said outlet member and the head with a chamber therebetween, and fastening means to secure the head and outlet member together, whereby the nozzle outlet is in a single part and a separable chamber is formed in the rear thereof.

8. A structure as specified in claim 7, said nozzle being formed to produce a fan shaped discharge in the plane of said joint.

9. A structure as specified in claim 7, said fastening means comprising a bolt inserted through the extension and the opposite wall of the head.

10. A structure as specified in claim 7, said head having a round bore leading to said nozzle, and said fastening means intersecting the axis of said bore.

Signed by me at Chicago, Illinois, this 26th day of April, 1918.

HALFTEN EUGENE OLSEN.
